TIRE

Richard T. Zimmerman, Tallmadge, Ohio, and Edmond E. Long, Orchard Lake, Mich., assignors to The Goodyear Tire & Rubber Company, Akron, Ohio, a corporation of Ohio

Filed Oct. 9, 1967, Ser. No. 8,916

Term of patent 14 years

(Cl. D90—20)

FIG. 1

FIG. 2

FIG. 1 is a perspective view of a tire, showing our new design, it being understood that the full line portion of the design is repeated throughout the circumference of the tire, the opposite side being substantially the same as that shown; and

FIG. 2 is an enlarged cross-sectional view thereof taken on line 2—2 of FIG. 1.

The dominant features of the design reside in the portions shown in full lines in the drawings.

We claim:

The ornamental design for a tire, substantially as shown and described.
